CLAIM

The ornamental design for an egg container, as shown and described.

DESCRIPTION

FIG. 1 is a perspective view of an egg container showing our new design;

FIG. 2 is a top plan view thereof;

FIG. 3 is a bottom plan view thereof;

FIG. 4 is a side elevational view thereof;

FIG. 5 is a front elevational view thereof;

FIG. 6 is a side elevational view opposite to the side shown in FIG. 4; and,

FIG. 7 is a rear elevational view thereof.

FIGS. 4-7 are on an enlarged scale.
